DESIGN FOR A GLOVE

Sylvan M. Straus, Gloversville, N. Y.

Application September 23, 1938, Serial No. 80,049

Term of patent 3½ years

To all whom it may concern:

Be it known that I, Sylvan M. Straus, a citizen of the United States of America, residing in Gloversville, in the county of Fulton and State of New York, have invented a new, original, and ornamental Design for a Glove, of which the following is a specification, reference being had to the accompanying drawing, forming part thereof, wherein

Figure 1 is a rear view of a glove showing my new design.

Figure 2 is a front view of the glove shown in Figure 1.

The characteristic feature of my design resides in the combination on the back of the specific glove of the zig-zag rows of perforations in the center panel and the plain perforations on the panels which include the forefinger and little finger, respectively, as shown.

I claim:

The ornamental design for a glove, substantially as shown and described.

SYLVAN M. STRAUS.
